UNITED STATES PATENT OFFICE

2,476,947

BUS OR CAR WINDOW CONSTRUCTION

Joseph Schunk, Union, N. J., assignor to The National Lock Washer Company, Newark, N. J., a corporation of New Jersey

Application November 23, 1944, Serial No. 564,816

3 Claims. (Cl. 189—73)

1

The present invention relates to improvements in bus or car window construction, and more particularly to the vertical supporting posts provided at each of the vertical side edges of the window frame and the vertical sash guides mounted thereon, and within which the window sash is slidably supported at each of its vertical side edges. An object of the invention is to provide a post and sash guide construction which will permit of the rapid assembly of the sash guide with the post, as well as the rapid disassembly, while at the same time providing a tight and secure connection between the sash guide and post.

It is a further object of the invention to provide a post and sash guide construction in which the usual bolts, screws, or similar means, employed for attaching the sash guide to the post are eliminated, and wherein interlocking means are employed for cooperation between the sash guide and the post, whereby through relative vertical movement of the sash guide it is interlockingly connected with the post. It is further proposed to provide automatic locking means, adapted to automatically engage in locking position upon assembly of the sash guide with the post to retain the sash guide against accidental displacement.

A further object is to provide post assembly means upon the sash guide, which may be conveniently connected thereto by the same holding means employed for other accessory parts of the sash guide. In the sash guide, illustrated by way of example, in the present disclosure, a removable stop constitutes one side of the sash guide for the purpose of removably retaining the slideable sash therein, and sash-retainer holding clips are provided for cooperation with this removable stop. It is proposed, according to the invention, to employ the same assembly rivets, or the like, for the holding clips and for the post assembly means of the sash guide. The illustrated type of sash guide also employs a series of pressure springs for exerting pressure upon the sliding sash, and it is proposed, according to the invention, to assemble these springs with the same rivets employed for assembling the sash-retainer holding clips and the post assembly means.

With the above and other objects in view, an embodiment of the invention is shown in the accompanying drawings, and this embodiment will be hereinafter more fully described with reference thereto, and the invention will be finally pointed out in the claims.

In the drawings:

Fig. 1 is a fragmentary elevation of the inner

2

side of the sash guide and post assembly of a window construction, according to the illustrated exemplary embodiment of the invention, a portion of the post being shown in vertical section.

Fig. 2 is a vertical sectional view, taken along the line 2—2 of Fig. 1.

Fig. 3 is a fragmentary side elevation of the sash guide, removed from the post, and with the removable stop, the window sash, and the rack strip member removed therefrom.

Fig. 4 is a front elevation of the sash guide, as seen in Fig. 3.

Fig. 5 is a front elevation of the removable side leg or stop of the sash guide.

Fig. 6 is an isometric perspective view of the several parts constituting the sash guide and post assembly, these parts being shown in extended separated relation to each other.

Fig. 7 is a horizontal sectional view, on an enlarged scale, taken along the line 7—7 of Fig. 1.

Similar reference characters indicate corresponding parts throughout the several figures of the drawings.

Referring to the drawings, the window sash part of the bus or car window structure, comprises the usual top rail 10, bottom rail 11, a pair of side straps 12 connecting the top and bottom rails at each side, the glass panel 13 being seated at its edges in the top and bottom rails and the side strips. Only one of the side straps and the cooperative sash guide and post assembly is shown. The side strap is of U-shape channel form in cross-section to receive the vertical edge of the glass panel, and is enclosed by a U-shaped cross-section facing strip 14 of felt or the like, secured thereto by cementing, so that it forms a fixed part of the movable window sash adapted to be raised and lowered with it. The bottom rail 11 is provided at its end with a horizontally movable latch bolt 15, normally projected by spring pressure, and adapted to be retracted through operation of a suitable latch lever (not shown), its nose end projecting through slots in the side strap and facing strip for engagement with the rack strip, as will presently more fully appear. The window opening comprises the usual sill 16, and side posts 17, the latter being connected at their upper ends to a suitable top rail (not shown).

Upon each of the side posts, only one of which is shown, there is mounted the sash guide assembly, and it is with the attachment means cooperating between the post and the sash guide that the present invention is especially concerned. According to the invention the post 17 is preferably in the form of a hollow sheet metal

pillar of generally rectangular cross-section, and in each of its side walls is provided, at suitable vertically spaced points with pairs of laterally spaced vertical slots 18. These slots are for the purpose of cooperation with the sash guide and are provided in each of the side walls for the purpose of assembly to a single post of the adjacent sash guides of adjacent windows. In the case of a single window the post will have the slots in one side wall only.

The sash guide comprises a fixed inside stop member of generally L-shape in cross-section comprising a flange 19 constituting one leg of the sash guide channel, and a base 20 provided at its post engaging side with vertically extending foot ribs 21 and 22 at its inner and outer edges for seating engagement with the post 17, these ribs providing a vertically extending recess between them in which is inserted a weather sealing strip 23 of felt or the like. The rib 22 at the outer edge of the fixed stop is adapted to removably receive the outer stop member 24 of the sash guide channel, and for this purpose is provided with a vertically extending groove 25, for receiving the rearwardly offset longitudinal rib 26 provided at the foot or base edge of the removable stop, and with a vertical recess 27, for receiving the locking flange 28 thereof, this locking flange being provided at suitably spaced points with cut-out notches 29 for cooperation with the sash-retainer holding clips provided upon the fixed stop member at spaced points, and presently to be more fully described. These notches permit the removable stop to be engaged with the grooved base of the fixed stop by engaging the holding clips in the notches, whereupon the removable stop is slidably moved vertically to bring the flange 28 into interlocking relation beneath the clips, as will presently more fully appear.

At points along the vertical line of the base 20 of the sash guide corresponding to the vertical spacing of the slots 18 of the post there are provided pairs of laterally spaced vertical slots 30, and at a point medially below each of these pairs of slots there is provided a rivet receiving hole 31, for the purpose of assembly of a spring grip finger member. This finger member comprises a rectangular base portion 32, provided at the upper portion of its side edges with right angularly bent finger extensions 33-33, each in the form of a downwardly directed hook of curved outline having a convexly curved gripping face in spaced opposed relation to the base 32. These fingers are engageable through the slots 30 and are provided at each of their upper sides with an upwardly projecting abutment shoulder 34 adapted to engage the outer side of the sash guide base 20 above the slots 30 through upward shifting of the finger member after insertion of the fingers 33 through the slots. In this upwardly-shifted assembled relation a rivet receiving hole 35 in the base 32 is in register with the hole 31 of the sash guide base 20, for the purpose of receiving the assembling rivet 36, which also assembles the sash-retainer holding clip and the pressure leaf spring, presently to be more fully referred to.

The sash-retainer holding clip is in the form of a rectangular plate 37 having a central rivet receiving hole 38 therein, and it is assembled by being superimposed upon by the base 32 of the spring grip finger member. At one edge the plate 37 is provided with an outwardly projecting flange 39, for engaging the side flange 19 of the sash

guide and for positioning the leaf spring, while at its other edge it is inwardly offset, as at 40, and projects over the locking flange receiving groove 25 for the purpose of having the flange 28 of the removable stop 24 slid into interlocking engagement beneath it, the clip being first disposed in the notch 29 of the flange 28 and the stop 24 being therefrom vertically moved to wedgingly engage the flange 28 beneath the clip.

10 The pressure leaf spring 41, which is also assembled by means of the rivet 36, may either be a single or a double bow type leaf spring, depending upon the particular location along the sash guide. In the illustrated embodiment the lowermost spring is a single bow type while the others are of double bow type. In either case, the spring 41 is provided with a mounting portion 42 seated upon the clip 37, with one edge engaged with the flange 39 to prevent relative turning movement, and this mounting portion is provided centrally with a rivet receiving hole 43, which registers with the rivet receiving holes 38, 35 and 31, so that the rivet 36 engaged through these several holes assembles the spring, the clip, and the spring-grip finger member upon the base 20 of the sash guide.

In the assembled relation of the window sash with the sash guide, the rack strip 44 is interposed between the springs 41 and the felt facing strip 14 of the window sash, the spring exerting lateral pressure upon the window sash through the rack strip, and the sash having inward lateral movement in the sash guide through lateral pressure applied to the sash to compress the springs.

30 The rack strip has an angular cross-section to provide a projecting flange 45 at one edge, which is slidably engaged with the inner side of the side leg 19 of the sash guide, and is confined in a vertically extending groove 46 formed by an inwardly extending flange 47 provided at the edge of the side leg 19, this flange 47 having bearing upon the side of the felt facing strip 14. Near its lower end the rack strip is provided with a rectangular opening 48 for receiving the projected sash lock bolt 15 in the lowered position of the window sash, and at suitably spaced points alongs the length of the strip there are provided rack teeth pocket members 49 for receiving the bolt to support the window in raised positions of adjustment. Upon the back of the rack strip at suitable locations to engage above and below one of the leaf springs 41, there are secured right angular shaped stop lugs 50 and 51 to hold the rack strip against relative vertical displacement.

55 In cooperative relation with one of the spring-grip finger members, there is provided a locking spring, and for this purpose the base 20 of the sash guide is provided with a vertical slot 52, in vertically aligned spaced relation above one of the slots 30, and with a rivet receiving hole 53 in spaced relation above the slot 52. The locking spring is in the form of an elongated rectangular leaf spring member 54 provided near its upper end with a rivet receiving hole 55, a rivet 56 being engaged through this hole 55 and the hole 53 in the base 20 to secure the spring to the sash guide. At its lower end the leaf spring member 54 is provided at one edge with a right angularly bent extension catch portion 57 having an upwardly extending locking tooth 58 at its end, this catch portion being projected through the slot 52 for the purpose of interlocking engagement with one of the slots 18 of the post, as will presently more fully appear.

70 In operation, the sash guide is assembled with

the post 17 by inserting the spring grip fingers 33 through the slots 18, the latter being slightly longer than the fingers. When so engaged, the latch portion 57 of the spring lock member is engaged with the side wall of the post at a point spaced above the upper end of the slot 18 in vertical alignment therewith, being sprung outwardly as the sash guide is pressed into engagement with the post. Thereupon the sash guide is forced vertically downward, so that the fingers move downwardly in the slots 18 and engage the inner surface of the side wall of the post below the slots with a wedging or binding action, the clearance between the gripping surfaces of the fingers and the inner side of the sash guide being such that as the side wall of the post is engaged between them, a spring reaction is set up in the spring grip finger member through the inherent springiness of the metal of which these members are formed. In practice, there may be a slight clearance between the abutment shoulders 34 of the fingers and the inner surface of the base 20 of the sash guide in the detached relation of the sash guide, so that as the sash guide is engaged with the post a slight tilting of the fingers may occur under spring reaction, bringing the shoulders 34 into tight abutment with the inner surface of the base of the sash guide, so that as the wall of the post is engaged beneath the fingers it is tightly wedged so that there is no likelihood of looseness. As the sash guide is moved downwardly to its assembled position the latch finger 57 of the locking spring 54 moves into register with the upper end of the slot 18 into alignment therewith and springs into latching position within the upper end of the slot, as shown in Figs. 1 and 2, thus retaining the sash guide against upward disengaging movement.

Upon assembly of the sash guide the removable outside stop member 24 is engaged in the groove 25 and slid downwardly to its locked position where the clips 37 wedgingly engage the flange 28. This locked position is secured by means of a set screw 59, provided in the removable stop in such relation that one side of the periphery of its head projects over its inner edge, where it is adapted to engage within a notch 60 in the outer edge of the fixed stop through screwing the set screw inwardly to bring the head into such engagement. Before engaging the removable stop 24, the rack strip 44 and the window sash are assembled with the sash guide.

In order to disassemble the sash guide the removable stop is disengaged and the rack strip and window sash removed from the sash guide. Thereupon the spring lock is pulled outwardly to disengage its latch portion 57 from the slot 18 of the post and the sash guide is forced upwardly to disengage the gripping fingers from the post, whereupon they are withdrawn through the slots 18.

I have illustrated and described a preferred and satisfactory embodiment of the invention, but it will be understood that changes may be made therein, within the spirit and scope thereof, as defined in the appended claims.

Having thus described my invention, what is claimed and desired to be secured by Letters Patent is:

1. In a window construction, a side post having a pair of laterally spaced vertical slots, a sash guide engageable with said side post and having a pair of laterally spaced vertical slots, and attaching hook means carried by said sash guide comprising a base portion secured to said sash guide at its inner side and a pair of vertically disposed hook extensions at each side of said base portion extending through said slots of said sash guide to its outer side, said hook extensions being engageable with said slots of said post and adapted to be interlocked with said post through relative vertical movement of said sash guide with respect to said post, each of said hook extensions having an abutment shoulder engaged with said sash guide at its outer side above said slots of said sash guide.
2. In a window construction, a side post having slot means, a sash guide engageable with said side post having slot means, attaching hook means carried by said sash guide comprising a base portion engaged with said sash guide at its inner side and hook extension means extending through said slot means of said sash guide to its outer side, a sash retainer clip engaged upon said base portion, and common securing means securing said base portion and said retainer clip to said sash guide, said hook extension means being engageable with said slot means of said post and adapted to be interlocked with said post through relative vertical movement of said sash guide with respect to said post.
3. In a window construction, a side post having slot means, a sash guide engageable with said side post having slot means, attaching hook means carried by said sash guide comprising a base portion engaging with said sash guide at its inner side and hook extension means extending through said slot means of said sash guide to its outer side, a sash retainer clip engaged upon said base portion, a sash pressure spring engaged upon said clip means, and common securing means securing said base portion, said clip means, and said spring to said sash guide, said hook extension means being engageable with said slot means of said post and adapted to be interlocked with said post through relative vertical movement of said sash guide with respect to said post.

JOSEPH SCHUNK.
